WATER FAUCET ATTACHMENT FOR IMPROVING THE TASTE OF DRINKING WATER

Donald F. Hassinger, Ann Arbor, Mich., assignor to
Pure Stat Corporation, Ann Arbor, Mich.

Filed Apr. 20, 1970, Ser. No. 22,510

Term of patent 14 years

Int. Cl. D23—01

U.S. Cl. D23—35

FIG. 1

FIG. 2

FIG. 3

FIG. 4

FIG. 1 is a side elevational view of a water faucet attachment for improving the taste of drinking water embodying my new design;

FIG. 2 is a rear elevational view thereof;

FIG. 3 is a front elevational view thereof; and

FIG. 4 is a top plan view thereof.

I claim:

The ornamental design for water faucet attachment for improving the taste of drinking water, as shown.
